UNITED STATES PATENT OFFICE

WALTER C. ASTRUP, OF CLEVELAND, OHIO, ASSIGNOR TO THE ASTRUP COMPANY, OF CLEVELAND, OHIO, A CORPORATION OF OHIO

DESIGN FOR AN AWNING ROD ELBOW

Application filed November 13, 1931. Serial No. 41,718. Term of patent 3½ years.

To all whom it may concern:

Be it known that I, WALTER C. ASTRUP, a citizen of the United States, residing at Cleveland, in the county of Cuyahoga and State of Ohio, have invented a new, original, and ornamental Design for Awning Rod Elbow, of which the following is a specification, reference being had to the accompanying drawings, forming part thereof.

Figure 1 is a perspective view of an awning rod elbow showing my new design; and Fig. 2 is a perspective view looking in another direction of the awning rod elbow shown in Fig. 1.

I claim:

The ornamental design for an awning rod elbow, as shown.

WALTER C. ASTRUP.
